UNITED STATES PATENT OFFICE.

KURT EVERE, OF CHARLOTTENBURG, GERMANY, ASSIGNOR TO GENERAL ELECTRIC COMPANY, A CORPORATION OF NEW YORK.

FUEL-Injector FOR OIL-ENGINES.

1,118,752.

Specification of Letters Patent.

Patented Nov. 24, 1914.

Application filed September 9, 1914. Serial No. 860,932.

To all whom it may concern:

Be it known that I, KURT EVERE, a subject of the King of Prussia, residing at Charlottenburg, Germany, have invented 5 certain new and useful Improvements in Fuel-Injectors for Oil-Engines, of which the following is a specification.

This invention relates to devices for spraying fuel oil into the cylinder of an 10 internal combustion engine, and especially one of the high compression type. In many of the so-called injectors or pulverizers heretofore employed for this purpose, the compressed air impinges on the oil and 15 drives it through the valve opening in direct lines. The oil particles tend to remain intact, except as they may be split up by the expansion of the compressed air. But inasmuch as the most efficient operation requires 20 an extreme subdivision of the fuel and its intimate intermingling with the air in order to form a perfect and quick burning mixture, the injectors or pulverizers above mentioned are not wholly satisfactory.

25 The object of my invention is to provide an injector or pulverizer which will give a good mixture of oil and air, and I accomplish this in the manner hereinafter set forth and particularly pointed out in the 30 claims.

In the accompanying drawings, Figure 1 is a sectional view of an injector or pulverizer embodying my invention, and Fig. 2 is a cross-section of the same on the line 35 2—2.

In the wall of the engine cylinder 1, which is provided with the usual water jacket 2, is arranged a receptacle 3 in which is inserted a plug 4, having a longitudinal 40 bore to receive a needle valve 5. The inner end of the receptacle is conical, to form a seat for the conical tip 6 of the valve, which controls the port 7 opening from the receptacle into the cylinder 1. The interior of 45 the plug is cored out to form a central chamber 8 surrounding the valve. A duct 9 communicates with this chamber, and enables a supply of fuel oil to be delivered thereto by a pump or other charge measuring device. 50 The outer portion of the plug fits tightly in the receptacle, but its inner portion is reduced in diameter, so as to leave an annular space around it. In said space is an annular member 10 fitting the receptacle tightly 55 but leaving an annular mixing chamber 11

between itself and the reduced portion of the plug. The annular member is preferably clamped between a shoulder 12 on the plug and a seat 13 in the receptacle. In the outer surface of the member 10 is a wide 60 circumferential groove 14 which communicates with a duct 15 in the plug through which a supply of compressed air is fed.

A plurality of small holes 16 run through the walls of the plug, connecting the central chamber 8 with the annular mixing chamber 11. A plurality of similar small holes 17 run through the annular member 10, connecting the groove 14 with the chamber 11. The two sets of holes deliver jets 70 of oil and air respectively to the mixing chamber 11, and are preferably so arranged that the jets of oil and air collide, so that the oil is broken up into spray and is thoroughly mixed with the air. In order to 75 still further commingle the oil and air, baffling devices are introduced into the chamber 11; preferably in the form of circumferential ribs 18 on the plug between the rows of holes 16. Similar ribs 19 may 80 be provided on the inner face of the annular member 10; preferably alternating in position with those on the plug, in which case the holes 17 will be located in the ribs, as shown, in order to oppose the holes in the 85 plug. The two sets of ribs leave an annular labyrinthine passage through which the oil and air will be forced by the pressure of the latter when the needle valve is opened. The impact upon the ribs, and the frequent 90 changes in direction, cause the oil to be still further subdivided and thoroughly mixed with the air, so that when the charge enters 95 the cylinder it is in a condition to burn promptly and steadily.

In accordance with the provisions of the patent statutes, I have described the principle of operation of my invention, together with the apparatus which I now consider to represent the best embodiment thereof; but 100 I desire to have it understood that the apparatus shown is only illustrative, and that the invention can be carried out by other means.

What I claim as new and desire to secure 105 by Letters Patent of the United States, is,—

1. An injector for oil engines comprising a receptacle, a plug therein having a central chamber and holes through the wall thereof, and a circumferentially grooved annular 110

member in said receptacle concentric with said plug and leaving an annular mixing chamber between them, said annular member having holes connecting the groove with the chamber, and said plug being provided with ducts for supplying oil to the central chamber and air to the groove.

2. An injector for oil engines comprising a receptacle, a plug therein having a central chamber and holes through the wall thereof, and a circumferentially grooved annular member in said receptacle concentric with said plug and leaving an annular mixing chamber between them, said annular member having holes connecting the groove with the chamber, and said plug being provided with ducts for supplying oil to the central chamber and air to the groove, the holes in said plug standing opposite those in said annular member.

3. A pulverizer for oil engines comprising a receptacle, a plug therein having a central chamber and holes through the wall thereof, and a circumferentially grooved annular member in said receptacle concentric with said plug and leaving an annular mixing chamber between them, said annular member having holes connecting the groove with the chamber, and said plug being provided with ducts for supplying oil to the central chamber and air to the groove, and having external ribs projecting into said mixing chamber.

4. A pulverizer for oil engines comprising

ing a receptacle, a plug therein having a central chamber and holes through the wall thereof, a circumferentially grooved annular member in said receptacle concentric with said plug and leaving an annular mixing chamber between them, said annular member having holes connecting the groove with the chamber, and said plug containing ducts for supplying oil to the central chamber and air to the groove, and ribs on said plug and annular member projecting into said mixing chamber.

5. A pulverizer for oil engines comprising a receptacle, a plug therein having a central chamber and holes through the wall thereof, a circumferentially grooved annular member in said receptacle concentric with said plug and leaving an annular mixing chamber between them, said annular member having holes connecting the groove with the chamber, and said plug containing ducts for supplying oil to the central chamber and air to the groove, and ribs on said plug and annular member projecting into said mixing chamber, and alternating with each other to form a labyrinthine passage for the oil and air.

In witness whereof, I have hereunto set my hand this 18th day of August, 1914.

KURT EVERE.
